UNITED STATES PATENT OFFICE.

GEORGE H. STEVENSON, OF RYE, NEW YORK, ASSIGNOR TO WESTERN ELECTRIC COMPANY, INCORPORATED, OF NEW YORK, N. Y., A CORPORATION OF NEW YORK.

WAVE METER AND SIMILAR ELECTRICAL DEVICE.

Application filed December 21, 1920 Serial No. 432,194

To all whom it may concern:

Be it known that I, GEORGE H. STEVENSON, a subject of the King of Great Britain, residing at Rye, in the county of Westchester, State of New York, have invented certain new, and useful Improvements in Wave Meters and Similar Electrical Devices, of which the following is a full, clear, concise, and exact description.

10 This invention relates to wave-meters and similar electrical apparatus, and more particularly, to means whereby the frequency calibration of such apparatus will not be rendered incorrect by the opening or closing 15 of a key connected to the circuits of the apparatus.

It is customary in the arts dealing with high frequency currents when wave-lengths are to be measured or compared, to make use 20 of a wave-meter, which for some purposes consists of a simple tuned receiver and detector, for high frequency waves and for other purposes consists of a low power generator. The usual manner of changing the 25 apparatus to form a local generator is to include in circuit a buzzer or self-interrupting electromagnet which causes the tuned circuit of the wave-meter to be excited at its resonant frequency. It has been found that 30 the key which serves to connect the buzzer into the circuit has a capacity between its contact blades of sufficient magnitude to cause the wave-length calibration which is correct with the key opened to be incorrect 35 when the key is closed or vice versa. This happens because the effective capacity of the key blades is in shunt with the tuning condenser of the tuned circuit when the key is opened. This capacity, in a particular instance, is of the order of 10×10^{-12} farads. A 40 capacity of this magnitude produces appreciable effects at radio frequencies. By placing additional insulated blades on the key and connecting these additional blades in 45 circuit so that when the key is closed their capacity will be substituted for the effective capacity introduced by the contact blades when the key is opened, the calibration may be made correct for either operative condition 50 of the apparatus.

The invention will be described in detail in connection with the accompanying drawings wherein Fig. 1 is a circuit diagram involving the essential features of the invention; and Fig. 2 is a cross-sectional view of 55 a cabinet in which the wave-meter is contained, showing the structure of the key and a push-button for operating it.

Referring to Fig. 1, the wave-meter circuit comprises a resonant high frequency 60 circuit including a coil 1 and a suitable variable condenser 2. The variable condenser is usually calibrated with a scale which indicates wave-lengths to which the tuned circuit will be resonant when it includes a 65 coil 1 of specified inductance. A detector 3, preferably consisting of a crystal of pyrites, but which may consist of any suitable detector of the crystal, thermionic or other type, is connected across the terminals of 70 the capacity 2 by a circuit 4. The circuit 4 includes a condenser 5 whose capacity is small compared to that of the condenser 2. By placing the condenser 5 in series with the detector 3, the effect of the capacity inherent 75 in the detector and its associated elements upon the tuning of the circuit 1, 2 is reduced to a negligible degree. In the case of a circuit dealing with the usual radio frequencies, that is, from one hundred thousand to two 80 million cycles per second, the capacity 5 should be of the order of 10×10^{-12} farads. A jack 6 is provided, by means of which the telephone receiver or other suitable indicating instrument may be connected around 85 the detector 3.

The circuit as so far described may be used to determine the wave-length of electromagnetic waves by introducing the coil 1 into the field of the waves whose frequency 90 is to be determined and varying the condenser 2 until a maximum indication is obtained in the telephone receiver. The calibration of the capacity 2 may be in wave-lengths or in frequencies which may be read off directly 95 or, if preferred, in capacity units from which the wave-length may be computed if the constants of the coil 1 are known.

Sometimes, however, it is desired to cause 100 the apparatus to generate oscillations of a

frequency to which the circuit 1, 2 is resonant. For this purpose, a buzzer 8 in circuit with the source of direct current 9 is provided. A resistance 10 of about 10 ohms may advantageously be connected around the electromagnet of the buzzer. When the contact blades 11 of the key K are closed, the buzzer is connected in shunt around the condenser 2. The buzzer thereupon operates and excites the circuit 1, 2 thereby causing therein the production of oscillations of the frequency to which the circuit is resonant. When the key K is opened, the blades 11 and 12 are separated and produce a capacity effect of appreciable magnitude. Since the capacity formed by the blades 11, 12 is connected in shunt to the condenser 2 through the circuit comprising the buzzer 8 and the source 9, the calibration of the condenser will not be correct when the key is closed if it is correct when the key is opened and vice versa. The electromagnet of the buzzer has a large distributed capacity so that it forms together with the small resistance 10, a path of relatively low impedance to high frequency current whereby the capacity of the blades 11 and 12 produces its full effect upon the capacity 2 when the buzzer contact 20 is in its normal closed condition.

An additional set of blades 13 is provided for the key K. Blades 13 are spaced away from and insulated from the blades 11 by the insulating material 14. When the key K is closed, the capacity between the blades 11 and 13 is caused to be in shunt to the condenser 2, the shunt circuit being through blades 12, 11, 13 and conductor 15. If this capacity is of such magnitude as to be equal in effect to the capacity between the blades 11 and 12 when they are separated, the calibration of the condenser 2 will be equally correct whether the key K is opened or closed. When the key K is closed, the capacity between blades 11 and 13 is short circuited through the buzzer circuit if the contact 20 of the buzzer is closed. However, oscillations are generated in the circuit 1, 2 substantially exclusively when the contact 20 is opened. The sequence of events is, first, closing of contact 20; second, increase of current flow through inductance 1; third, opening of contact 20; fourth, production of a damped train of oscillations in circuit 1, 2. The oscillations in circuit 1, 2 fall to a negligible value by the time contact 20 closes again. High frequency oscillations occur, therefore, principally when contact 20 is open, during which time capacity 11-13 is in effective shunt to capacity 2. The small capacity between the terminals of contact 20 is neglected as this will introduce an error too small to be considered.

As shown in Fig. 2, the wave-meter as a whole, except coil 1, is provided with an

enclosing and shielding cabinet 16 having a hinged lid 17 upon which a block 18 is mounted. When the lid 16 is raised, a push-button 19 is accessible. By pulling out or raising the button 19, the key K may be closed, by pushing it in, the key will be opened. When the lid 17 is closed, the block 18 is arranged to force the push-button 19 down to the farthest extent thereby opening the key K and preventing the wave-meter being put away with the key left accidentally closed so that the battery 9 would run down and become exhausted.

Although this invention has been described as embodied in a wave-meter it is obvious that the principle involved is capable of much broader application and all such applications are considered as falling within the scope of this invention.

What is claimed is:

1. An electric circuit including a circuit closing device having a normally open and a normally closed position, the elements of said device forming, when open, an electric condenser of capacity sufficiently large to interfere with the functioning of said circuit in combination with an element which substitutes a capacity of approximately equal value in the same electrical position in said circuit when said device is operated to close said circuit.

2. In a wave-meter, a tuned circuit containing a capacity element, a key in a circuit in shunt to said capacity element, two blades on said key forming a capacity in shunt to said capacity element when said key is opened, and an additional blade of said key forming a capacity of substantially equal effective value in shunt to said element when said key is closed.

3. In a high frequency electrical apparatus a capacity element, a circuit-closing element for closing a circuit in shunt to said capacity, said circuit-closing element when opened introducing a reactance in shunt to said capacity element, and means automatically introduced in shunt to said capacity element by the closing of said circuit-closing element having an effective reactance substantially equal to the reactance introduced by said circuit-closing element when opened.

4. In a high frequency electrical apparatus a capacity element, a circuit-closing element for closing a circuit in shunt to said capacity, said circuit-closing element when opened constituting a capacity in shunt to said capacity element, and means introduced in shunt to said capacity element by the closing of said circuit-closing element having an effective capacity substantially equal to the capacity of said circuit-closing element when it is opened.

5. A wave-meter comprising a tuned circuit containing a capacity element, a key for

connecting a buzzer in shunt to said capacity element, the blades of said key when opened constituting a capacity in shunt to said capacity element through a circuit including said buzzer, and auxiliary blades on said key forming with at least one of said first mentioned blades, a capacity in shunt to

said capacity element through another circuit when said key is closed.

In witness whereof, I hereunto subscribe my name this 18th day of December, A. D. 1920.

GEORGE H. STEVENSON.
